APPARATUS FOR ROD MILLS

Einer W. Larsen, Chicago, Ill., assignor to
Western Electric Company, Incorporated, New
York, N. Y., a corporation of New York

Application December 26, 1929, Serial No. 416,388

19 Claims. (CL 80—43)

This invention relates to apparatus for rod mills, and more especially to apparatus for controlling and directing a rod between successive reductions of a rod mill.

5 The primary object of this invention is to provide a simple, efficient, and practical apparatus for receiving and dispensing rods in the process of reduction and insures the proper, accurate, and positive directing of the rod.

10 According to the objects of the invention, an element is actuated by the movement of a rod for locking a receiving table until the entire rod is thereupon, and an auxiliary means is provided for releasing the table, whereby the table 15 may be moved by the weight of the rod so as to pass the rod to reducing rolls, after which the table is moved by counterweights to its receiving position.

Other objects will be apparent from the following detailed description when considered in connection with the accompanying drawings, wherein

Fig. 1 is a fragmentary top plan view of the apparatus for receiving and dispensing rods;

25 Fig. 2 is an elevational view of the apparatus shown in Fig. 1;

Fig. 3 is an enlarged top plan view of the table locking and releasing mechanism;

Fig. 4 is a rear elevational view of the mechanism shown in Fig. 3 and

30 Fig. 5 is an enlarged end elevational view of the apparatus, showing the table in full lines in the receiving position and in dotted lines in the dispensing position.

35 Referring particularly to Figs. 1 and 2, the apparatus for receiving and dispensing rods consists of a table 10 formed of a plurality of table sections which are pivotally mounted upon a common shaft 11. The shaft 11 is pivotally supported by bearing members 12 which are mounted upon base units 13. The table sections are provided with receiving portions 14 (Figs. 1 and 5) which are normally in a horizontal position and stationary guide members 15

40 which are normally in a vertical position. A movable rod guide 16 extends above the free edge 17 (Fig. 5) of the table 10 when the table is in the receiving position, and is carried by brackets 18 which are mounted upon and keyed to the shaft 11. The brackets 18 are arranged with integral arms 19 which have roller engaging surfaces 20 thereupon.

45 The brackets 18 are operatively associated with actuating levers 21 which in turn are fixed to an auxiliary shaft 22. The levers 21 have rollers

23 which are disposed in engagement with the roller engaging surfaces 20 of the arms 19. Rollers 24 also form a part of the levers 21 and are disposed in engagement with roller engaging plates or portions indicated at 25 which are disposed upon the under surface of the receiving portion 14 of the table 10. Counterweights 26 are fixed to the shaft 11 for a purpose herein-after described.

50 A rigid tapered chute or guide 27, which is rigidly mounted upon the base units 13, is adapted to receive the bars passed from the table and direct the bars into a rolling apparatus indicated as 28.

The means for locking the table in the receiving position is shown in Figs. 3 and 4, and consists of an actuating lever 29 which may be termed a trip gate and which is fixed to a vertical shaft 30. The actuating lever 29 extends over a stationary table 31 which is in general alignment with the table 10 when the latter is in receiving position. A gear segment 32 is mounted upon the shaft 30 and arranged to be actuated by the actuation of the lever 29. The segment 32 is in mesh with a toothed portion 33 of an actuating cam 34, which is pivotally mounted at 35, and provided with a cutaway cam portion 36 which tapers into a retaining cam portion 37 as indicated at 38. A retaining latch 39 is pivotally mounted at 40

55 and is provided with a roller 41 which is held in engagement with the actuating cam 34 by means of a tension spring 42. The latch 39 is provided with a jaw portion 43 which is arranged to engage with the adjacent arm 19 at 44 so as to hold table 10 positively in the receiving position. A tension spring 45 has one end adjustably secured to the segment 32, by the adjustable means indicated at 46, and the other end secured to the adjacent base unit 13. 60 A safety spring 47 has one end secured to the segment 32 at 48 and the other end secured to a safety lever 49, which is mounted upon the shaft 30 and which is arranged to engage with a pin 50, the latter being carried by the segment 32. A stop 51 is provided for holding the segment 32 against further movement in one direction.

65 From the foregoing description of the various parts of this apparatus, the operation thereof may be more clearly understood. The bar, indicated at 52, in passing from the preceding operation, passes with sufficient force to carry it onto the table 10 and beyond the actuating mechanism shown in Fig. 3 without additional 70

moving force. As the bar moves across the stationary table 31 the lever 29 is actuated, due to the engagement of the bar therewith, thus actuating the segment 32 against the tension of the spring 45 and imparting a clockwise rotative movement to the actuating cam 34. This movement of the actuating cam 34, imparts an inward movement to the retaining latch 39, about its pivot 40, due to the engagement of the roller 41 with the same surface 38. The latch 39 is held in this position by the engagement of the roller 41 with the cam surface 37 during engagement of the bar with the actuating lever 29.

15 As soon as the bar has passed the actuating mechanism and has reached a position entirely upon the table 10, the actuating lever 29 will be released, allowing the spring 45 to return the segment 32 to its normal position, thus rotating the actuating cam 34 in a counter-clockwise direction and allowing the latch 39 to be withdrawn from its engagement with the arm 19 by means of the spring 42, and by means of the roller 41 engaging with the cam surfaces 38 and 36.

Immediately upon the release of the latch 39, the table 10 will be moved about the shaft 11 as a pivot due to the weight of the bar upon the table and consequently a faster movement 30 to the movable rod guide 16 due to the engagement of the lever 21 therewith will result. It will be observed by viewing Fig. 5 that the arm of the lever 21 upon which the roller 24 is mounted, is relatively short compared with the 35 arm upon which the roller 23 is mounted.

Therefore, the movement of the lever 21, due to its engagement with the table 10, will move the movable guide 16 faster than the table, thus 40 positioning the movable guide beyond the free edge of the table when the table is in the lowermost position. When the table is in this position the bar is allowed to pass from the table upon the chute 27 and into the rolling apparatus 28.

45 After the bar has passed from the table 10, the counter-weights 26 will impart a movement to the brackets 18, thus moving the guide 16 into its normal position, and at the same time moving the table 10 into its normal position, due to the operative engagement of the lever 21 with the table. The table is now in readiness for receiving another or succeeding bar.

With this construction, it is obvious that a 55 positive means is provided for receiving and dispensing the bars from one operation to another, and that the dispensing of the bars is accomplished by an efficient mechanical means which is actuated by the movement and weight of the bar. It will be further observed that the 60 device is positive in its action and serves to prevent the actuation of the table 10 until the bar has completely passed thereupon as the actuating mechanism cannot be released until the bar has passed this point and onto the table.

65 Although a specific form of apparatus has been disclosed as exemplifying the embodiment of the invention, it is understood that other forms of apparatus might be used without departing from the spirit and scope of the present invention.

What is claimed is:

1. In an apparatus for receiving and dispensing bars, a table member, a bar guide associated with an edge of said table member, means

actuated by movement of said table member for moving said guide with respect to said edge of the table when said table is moved in one direction, and means for moving said guide for moving said table member in the opposite 80 direction.

2. In an apparatus for receiving and dispensing bars, a table member for receiving a bar, means for holding said table against movement by the movement of the bar onto said table, said means comprising a latch for engaging with said table, and means actuated by the movement of the bar for actuating said latch. 85

3. In an apparatus for receiving and dispensing bars, a table member for receiving a bar, means for holding said table against movement by the movement of the bar onto said table, said means comprising a latch for engaging with said table, means actuated by the movement of the bar for actuating said latch, and means for releasing said latch when said latch actuating means is released. 90

4. In an apparatus for receiving and dispensing bars, a table member for receiving a bar, means for pivotally supporting said table member, a bar guide associated with an edge of said table member mounted upon said pivotal supporting means, and means operatively connecting said table member with said guide member for moving said guide with respect to said edge 105 of the table member when said table member is moved in one direction to permit the dispensing of the bar from the table by the action of gravity.

5. In an apparatus for receiving and dispensing bars, a table member, means for pivotally supporting said table member, a bar guide associated with an edge of said table member mounted upon said pivotal supporting means, and means operatively connecting said table member with said guide member for moving said guide with respect to said edge of the table member when said table member is moved in one direction, and means for moving said guide for moving said table member in the opposite 120 direction. 110

6. In an apparatus for receiving and dispensing bars, a table member for receiving a bar, means for pivotally supporting said table member, a bar guide associated with an edge of said 125 table member mounted upon said pivotal supporting means, and means operatively connecting said table member to said guide for moving said guide with respect to said edge of the table member when said table member is moved in one direction by the bar for dispensing the bar. 130

7. In an apparatus for receiving and dispensing bars, a table member for receiving a bar, means for pivotally supporting said table member, a bar guide associated with an edge of said 135 table member mounted upon said pivotal supporting means, means operatively connecting said table member with said guide for moving said guide with respect to said edge of the table member when said table member is moved in one direction by the bar for dispensing the bar, and means for receiving the bar dispensed from said table member. 140

8. In an apparatus for receiving and dispensing bars, a table member for receiving a bar, means for pivotally supporting said table member, a bar guide associated with an edge of said 145 table member mounted upon said pivotal supporting means, means operatively connecting said table member with said guide for moving said 150

- guide with respect to said edge of the table member when said table member is moved in one direction by the bar, and means for moving said guide for moving said table member in the opposite direction.
9. In an apparatus for receiving and dispensing bars, a movable table member having a plane surface normally positioned horizontally for receiving and supporting a bar, means adapted to be actuated by the bar previous to its moving onto said table for holding said table member against movement for dispensing the bar, and means for releasing said table member holding means when the bar is received by said table member.
10. In an apparatus for receiving and dispensing bars, a table member for receiving a bar, a bar guide associated with an edge of said table member, and means actuated by movement of said table member for moving said guide across said edge during movement of the table member to permit the dispensing of the bar from the table by the action of gravity.
11. In an apparatus for receiving and dispensing bars, a movable table member having a plane surface normally positioned horizontally for receiving and supporting a bar, and means for automatically holding said table against movement for dispensing the bar by the movement of the bar onto said table, said means including a member arranged in the path of the bar before it moves onto the table.
12. In an apparatus for receiving and dispensing bars, a movable member having a plane surface normally positioned horizontally for receiving and supporting a bar, means for holding said member against movement, and means actuated by the movement of the bar thereon for actuating said holding means.
13. In an apparatus for receiving and dispensing bars, dispensing means actuated by a bar, said means including a member pivotal about a fixed axis and having a plane surface normally positioned horizontally upon which the bar is received and supported until dispensed, and means for returning said dispensing means to normal position after the bar is dispensed.
14. In an apparatus for receiving and dispensing bars, a movable member having a plane surface normally positioned horizontally for receiving and solely supporting a bar, means actuated by the movement of the bar thereon for holding said member against movement, and means for releasing said member whereby said member may be actuated.
15. In an apparatus for receiving and dispensing bars, a movable member for receiving and supporting a bar, a movable guide member for preventing accidental displacement of the bar from the supporting member, and means responsive to a movement of the supporting member for moving the guide member relative to the supporting member to thereby cause the bar to be dispensed from the supporting member.
16. In an apparatus for receiving and dispensing bars, a movable member for receiving and supporting a bar and gravity actuated by the weight of the bar for dispensing the bar, holding means for preventing gravity actuation of said member, and means actuated by the bar for controlling said holding means and thereby said gravity actuation of the member.
17. In an apparatus for receiving and dispensing bars, a movable member for receiving and supporting a bar and gravity actuated by the weight of the bar for dispensing the bar, holding means for preventing gravity actuation of said member, and means disposed in the path of the bar operatively connected to said holding means and effective while engaged by the bar to render the holding means effective for preventing the gravity actuation of the member.
18. In an apparatus for receiving and dispensing bars, a movable member for receiving and supporting a bar and gravity actuated by the weight of the bar for dispensing the bar, holding means for preventing gravity actuation of said member, and means disposed in the path of the bar operatively connected to said holding means and effective while engaged by the bar to render the holding means effective for preventing the gravity actuation of the member, said means disposed in the path of the bar being effective upon the disengagement of the bar therefrom to cause an actuation of the holding means for releasing the gravity actuated member.
19. In an apparatus for receiving and dispensing bars, a movable member for receiving and supporting a bar and gravity actuated to dispense the bar, a movable guide member for preventing accidental displacement of the bar from the supporting member, and means responsive to a gravity actuation of the supporting member for moving the guide member relative to the supporting member.
